US0D1039918S

(12) **United States Design Patent** (10) **Patent No.:** **US D1,039,918 S**
(45) **Date of Patent:** **** Aug. 27, 2024**

(54) **COMBINED FOOD WRAP AND PLACEMAT**

(71) Applicant: **Scrubza, LLC**, Catonsville, MD (US)

(72) Inventor: **Jason Mah**, Catonsville, MD (US)

(73) Assignee: **SCRUBZA, LLC**, Catonsville, MD (US)

(**) Term: **15 Years**

(21) Appl. No.: **29/884,587**

(22) Filed: **Feb. 13, 2023**

<https://www.amazon.com/incley-Reusable-Container-Collapsible-Silicone/dp/B0BLG8P72D> (Year: 2022).*

Incley Folding Dinner Plates, first available Nov. 4, 2022, Amazon, [online], [site visited Aug. 30, 2023], Available from internet URL:

FIG. 1 is a bottom plan view of a first embodiment of a combined food wrap and placemat showing my new design;

FIG. 2 is a top plan view thereof;

FIG. 3 is a left side view thereof, the right side view being a mirror image thereof;

FIG. 4 is a front side view thereof;

FIG. 5 is a rear side view thereof;

FIG. 6 is a partial cross-sectional view of the first embodiment of the combined food wrap and placemat taken along line 6-6 in FIG. 1;

FIG. 7 is a partial cross-sectional view of the first embodiment of the combined food wrap and placemat taken along line 7-7 in FIG. 1;

FIG. 8 is a partial cross-sectional view of the first embodiment of the combined food wrap and placemat taken along line 8-8 in FIG. 1;

FIG. 9 is a top perspective view of the first embodiment of the combined food wrap and placemat shown in a first position of use;

FIG. 10 is a perspective view of the first embodiment of the combined food wrap and placemat shown in a second position of use;

FIG. 11 is a perspective view of the first embodiment of the combined food wrap and placemat shown in a third position of use;

(Continued)

FIG. 12 is a perspective view of the first embodiment of the combined food wrap and placemat shown in a fourth position of use;

FIG. 13 is a perspective view of the first embodiment of the combined food wrap and placemat shown in a fifth position of use;

FIG. 14 is a perspective view thereof, shown rotated 180 degrees;

FIG. 15 is a plan view of the closure feature of the first embodiment of the combined food wrap and placemat shown separately for clarity of the disclosure;

FIG. 16 is a perspective view of the closure feature of the first embodiment of the combined food wrap and placemat shown separately for clarity of the disclosure;

FIG. 17 is a bottom plan view of a second embodiment of a combined food wrap and placemat showing my new design;

FIG. 18 is a top plan view thereof;

FIG. 19 is a partial cross-sectional view of the second embodiment of the combined food wrap and placemat taken along line 19-19 in FIG. 17;

FIG. 20 is a partial cross-sectional view of the second embodiment of the combined food wrap and placemat taken along line 20-20 in FIG. 17;

FIG. 21 is a partial cross-sectional view of the second embodiment of the combined food wrap and placemat taken along line 21-21 in FIG. 17;

FIG. 22 is a top perspective view of the second embodiment of the combined food wrap and placemat shown in a first position of use;

FIG. 23 is a perspective view of the second embodiment of the combined food wrap and placemat shown in a second position of use;

FIG. 24 is a perspective view of the second embodiment of the combined food wrap and placemat shown in a third position of use;

FIG. 25 is a perspective view of the second embodiment of the combined food wrap and placemat shown in a fourth position of use;

FIG. 26 is a perspective view of the second embodiment of the combined food wrap and placemat shown in a fifth position of use;

FIG. 27 is a perspective view thereof, shown rotated 180 degrees;

FIG. 28 is a plan view of the closure feature of the second embodiment of the combined food wrap and placemat shown separately for clarity of the disclosure;

FIG. 29 is a perspective view of the closure feature of the second embodiment of the combined food wrap and placemat shown separately for clarity of the disclosure;

FIG. 30 is a left side view of the second embodiment of a combined food wrap and placemat, the right side view being a mirror image thereof;

FIG. 31 is a front side view thereof; and,

FIG. 32 is a rear side view thereof.

The sandwich shown in broken line in FIGS. 9-12 and 22-25 is environment and forms no part of the claimed design. All

other broken lines show portions of the combined food wrap and placemat that form no part of the claimed design.
